SURGICAL SUTURE

John H. Alcamo, 321 S. 9th St., Newark, N.J.
Original application Aug. 13, 1956, Ser. No. 603,546, now
Patent No. 2,983,028, dated June 13, 1961. Divided
and this application Apr. 20, 1961, Ser. No. 105,256
4 Claims. (Cl. 128—335.5)

This invention relates to a surgical suture, and this application is a division and a continuation in part of my application titled Surgeon's Suturing Device, Serial No. 603,546, filed August 13, 1956, now Patent No. 2,983,028. The suture of the present invention is desirable for use in the mentioned suturing device, but is also advantageous in manual sewing of incisions and wounds.

The invention is a suture so formed that it prevents slippage in sutured incisions or wounds, and is shown as of non-uniform diameter or as non-straight. It is illustrated as being a fiber, filament, or thread, of "gut" or other suitable material, the surface of which, at least in part, is roughened, so that it will effectively hold the sewed incision or wound. The roughening may take the form of raised projections, or depressions, or teeth, as, for example, barbs or spicules, adapted to snag or penetrate or press into the flesh and thereby prevent slippage of the suture after each stitch. The suture may also be sinuous, with or without other irregularities. This anti-slipping action of a suture is obviously desirable in sewing incisions or wounds because the flesh is moist and therefore slippery. My improved suture therefore enables the surgeon to make a tighter seam.

The accompanying drawings illustrate various forms of suture constructed as stated broadly above.

In the drawings:

FIGURE 1 shows an incision closed by a suture of the invention;

FIG. 2 shows the suture in the form of a loop stitch and in process of closing an incision;

FIGS. 3 through 7 show incisions closed by different forms of suture, with the lower ends of the latter in section;

FIGS. 8 through 12 show still further modifications of the suture;

FIG. 13 shows adjacent sections to be sewed, with a loop of suture through one of the sections;

FIG. 14 shows a broken length of a modified form of suture, in which roughened sections alternate with smooth sections;

FIG. 15 is an enlarged fragmentary view of FIG. 14; and

FIG. 16 is a section of a suture characterized by knurling.

Referring to the drawings for a detailed description, in FIGS. 3 through 7 the parts to be sewed are designated S, and the projections on sutures are designated respectively 2, 2a, 2b, 2c and 2d. In FIGS. 8 through 12, the projections are 1e, 1f, 1g, 1h, and 1i respectively.

In FIG. 13, the designations are the same as those of FIG. 1, in which S designates the sutured flesh, 1 the suture, and 2 the projections thereon.

FIG. 3 shows barbs or spicules 2 projecting from the

2

body of the suture and directed toward the trailing end thereof and at acute angles thereto. FIG. 4 shows barbs 2a somewhat similar to those of FIG. 3 but more regularly arranged. FIG. 5 shows projections 2b terminating in curved edges. FIG. 6 shows projections 2c at right angles to the suture body, but which are flexed when the suture passes through flesh. FIG. 7 shows projections 2d having curved edges alternating in directions and each extending part way around the suture body. FIG. 8 shows a spiral projection 1e. FIG. 9 illustrates projections 2f, having sharp curved edges. FIG. 10 shows a suture having spherically triangular curved facets forming projections 2g. FIG. 11 shows annular notched rings which provide projections 2h, and FIG. 12 illustrates a non-straight or, more specifically, a sinuous, suture body having teeth or barbs 2i. It will be noted that all the projections, with the exception of those of FIG. 6, are directed to one end of the suture, to allow it to glide smoothly in one direction, and to so engage the flesh as to prevent separation of the sutured parts. As to the projections of FIG. 6, these flex as they pass through the flesh as shown, and then prevent slippage of the suture.

FIGS. 14 and 15 show a suture having roughened or barbed section B alternating with smooth or unbarbed sections A. The lengths and relative lengths of these sections will vary with conditions in which the suture is used, it being intended that the roughened or barbed sections shall be confined to within the flesh, with the smooth sections lying over and under the same, to avoid irritation. FIG. 16 is a fragmentary view of a suture forming a modification of that shown in FIGS. 14 and 15 wherein knurled portions C are substituted for the barbed sections B.

What is claimed is:

1. An elongate cord of a diameter and tensile strength adapted for sewing and holding human flesh, and comprising a body portion and sharp-edged, resilient barbs projecting therefrom, at acute angles relative to, and directed toward, the trailing portions of the body, and adapted to yield toward the body when pulled through the flesh and of a size adequate to penetrate the flesh when the cord is pulled against the barbs.

2. The cord specified in claim 1, in which said barbs are pointed at their free ends.

3. The cord specified in claim 1 in which the edge of the barbs are curved.

4. The cord specified in claim 1, in which the barbs form a helix.
